(57) **CLAIM**

The ornamental design for a soil moisture sensor, as shown and described.

DESCRIPTION

FIG. 1 is a front perspective view of my new design for a soil moisture sensor;

FIG. 2 is a front elevation view of the soil moisture sensor shown in FIG. 1;

FIG. 3 is a rear elevation view of the soil moisture sensor shown in FIG. 1;

FIG. 4 is right side view of the soil moisture sensor shown in FIG. 1;

FIG. 5 is a left side view of the soil moisture sensor shown in FIG. 1;

FIG. 6 is a bottom plan view of the soil moisture sensor shown in FIG. 1;

FIG. 7 is a top plan view of the soil moisture sensor shown in FIG. 1;

FIG. 8 is a front perspective view of another configuration of a soil moisture sensor;

FIG. 9 is a front elevation view of the soil moisture sensor shown in FIG. 8;

FIG. 10 is a rear elevation view of the soil moisture sensor shown in FIG. 8;

FIG. 11 is right side view of the soil moisture sensor shown in FIG. 8;

FIG. 12 is a left side view of the soil moisture sensor shown in FIG. 8;

FIG. 13 is a bottom plan view of the soil moisture sensor shown in FIG. 8; and,

FIG. 14 is a top plan view of the soil moisture sensor shown in FIG. 8.

Broken lines shown in the drawings form no part of the claimed design.
